UNITED STATES PATENT OFFICE

WOLFGANG HERMANN, OF CHICAGO, ILLINOIS, ASSIGNOR TO METAL SPECIALTIES MANUFACTURING CO., OF CHICAGO, ILLINOIS, A CORPORATION OF ILLINOIS

STRIP-SERVING MACHINE

Application filed May 31, 1928. Serial No. 281,802.

38 The present invention pertains especially to the strip-moistening means of a strip-serving machine.

39 The present application is in part a continuation of my application Serial No. 157,201, filed December 27, 1926.

40 The invention is illustrated in a preferred embodiment in the accompanying drawings, in which—

41 Fig. 1 is an end elevational view of a strip-serving machine embodying the invention; Fig. 2, an enlarged broken vertical sectional view taken as indicated at line 2—2 of Fig. 1; Fig. 3, a perspective view, partly in section, of a moistening pad and associated presser-member; Fig. 4, a perspective view of the font on which the device shown in Fig. 3 is removably mounted; Fig. 5, a vertical sectional view of a modified form of moistener-pad; Fig. 6, a view similar to Fig. 5, but showing the wick-element removed; Fig. 7, a horizontal section taken as indicated at line 7 of Fig. 6; Fig. 8, a sectional view showing the wick and the inner form over which the wick is folded; and Fig. 9, a broken vertical sectional view of strip serving machine equipped with the modified form of moistener pad shown in Fig. 5.

42 Referring to Figs. 1-4, A designates the frame of a strip-serving machine; B, strip-feeding means mounted in the frame near the delivery end thereof; C, a water font removably supported in the frame A and withdrawable through the delivery end of the frame; D, a moistener pad demountably carried by the font; and E, strip-severing means mounted on the frame.

43 The frame A may be of any suitable construction. It is shown as comprising a base casting A' and an upper casting A² mounted thereon. The frame is hollow and its sides are connected by an inclined web 1 over which the strip 2, usually a gummed tape strip, passes. The frame has a top wall 1^a which is provided with a slot 1^b.

44 The feed mechanism B comprises a shaft 3 upon which is secured a ratchet-wheel 3^b; a feed-disk 4 journalled on the shaft adjacent the ratchet-wheel and equipped with a pawl 4^a; and a small idle roll 5 journalled in a pivoted presser-member 6 which is supported on a pivot 7 and equipped with a spring 8 which normally holds the paper strip pressed against the feed-disk 4.

45 The shaft 3 is equipped with a crank 3^a by means of which the shaft 3 may be actuated in a counter-clockwise direction, as viewed in Fig. 2. A spring 9 serves to return the crank to its normal position, where it engages an adjustable stop 10.

46 In advance of the idle presser-wheel B is located a removable presser-plate 11.

47 The font C is preferably drawn from sheet brass. It is an open-topped vessel having a spout-portion 12 pressed outwardly from its front wall. It is seated on a plate 13 which is secured to lugs 14 with which the member A' is provided. The plate 13 is provided at its rear end with an upstanding lug 13^a and at its front end with an upstanding lug 13^b. The front wall of the casting A' is cut away, as indicated at 15, so that the font can be removed by lifting its front end somewhat and then withdrawing the font.

48 The device D comprises a sheet-metal clip 16 of hollow rectangular form; an absorbent pad 17 adjustably mounted in the member 16; and a U-formed bracket-member 18 having a web-portion 18^a and having arms 18^b which are secured to the end walls of the member 16 by means of rivets 19. The arms 18^b are provided with notches 20 which are adapted to engage the upper marginal portions of the front wall of the font at the points 21, flanking the chute, or spout-portion, 12.

49 The bracket 18 is provided with ears 18^c which are perforated to receive a pintle 22 upon which is pivotally supported a sheet-metal presser-member 23 which has a

- weighted front end-portion 23^a. The front end-portion of the presser-member 23 rests upon the upper edge of the absorbent pad 17, which may be a felt pad. The front wall 5 of the member 16 is provided with perforations 24 which may receive pins, or nails, 25 which pass through the perforations and through the pad. Thus, the pad is adjustably supported in the clip 16.
- 10 In the modification shown in Figs. 6-8, D' designates a demountable pad equipped with a presser-member, which may be used in lieu of the device D. The modified device comprises an outer clip 26; an inner form 27; and a wick 28. The clip 27 corresponds in a general way with the clip 16, shown in Fig. 3. It is carried by a U-shaped bracket 18 of the construction shown in Fig. 3; and this bracket carries the presser-member 23 of the construction shown in Fig. 3. The bracket 18 and the presser-member mounted thereon corresponds substantially with the corresponding members shown in Fig. 3, and the parts are similarly designated.
- 15 The member 27 is an expansible member made from sheet-metal. It is of general U-form having a web 27^a and depending arms 27^b, one of which is equipped at its lower end with a stop 27^c.
- 20 The inner member 27 has the wick 28 passing about the same. As thus assembled, the wick and inner-form member may be inserted into the clip 26, so that the wick will be clamped between the inner and outer members. The clip 26 is equipped at its lower end with a stirrup 29 which has a web-portion 29^a and arms 29^b. The arms are connected, by pivots 30, with the lower portions of the end walls of the clip 26. As shown in Fig. 25, the stirrup 29 may be swung to clamp a portion 28^a of the wick beneath the lower end of the form 27, the stop 27^c serving to limit the swinging movement.
- 30 The cutter E is shown as comprising a slotted plate 31 mounted on the side walls of the frame in front of the top wall 1^a; a horizontal shearing blade 32; a pivoted shearing blade 33; and a link 34 which is connected with an arm 35 pivoted on the shaft 3. The arm 35 is normally held in the position shown in Fig. 2 by means of a latch-arm 36 mounted on a rock-shaft 37 which is equipped with a trip-arm 38 adapted to be struck by the crank 3^a at the end of the feeding operation.
- 35 The arm 35 is adapted to be thrown downwardly, when the latch is released, by means of a spring (not shown).
- 40 The form of device shown in Figs. 5-8 possesses some advantages over the form shown in Fig. 3. The wick 28 may be adjusted from time to time to bring a fresh portion of the wick into operative position with relation to the mucilage on the strip 2 which is fed over the wick.
- 45 Water may be poured into the font through

the chute 12, when necessary. The font and the pad supported thereon may be withdrawn from the machine, for any desired purpose.

The foregoing detailed description has been given for clearness of understanding only, and no unnecessary limitations should be understood therefrom, but the appended claims should be construed as broadly as permissible, in view of the prior art.

70 What I regard as new, and desire to secure by Letters Patent, is:

75 1. In a machine of the character set forth, the combination of a frame provided at its front end with an opening, a water font housed within said frame and removable through said opening, a bracket detachably mounted on said water font, a clip carried by said bracket, and a wick and inner-form member removably inserted in said clip.

80 2. In a machine of the character set forth, the combination of a frame, a water font removably-supported in the front portion thereof, a holder detachably supported on said water font, a capillary moistener-element mounted in said holder, and a presser-member movably mounted on said holder and co-acting with said moistener-element.

85 3. In a machine of the character set forth, the combination with a water font, a holder-bracket detachably carried thereby and having a web-portion, a capillary moistener-element engaged by said bracket and having a portion disposed adjacent the front edge of said web, and a presser-member pivotally mounted on said holder-bracket and having its front portion coacting with said moistener-element.

90 4. In means of the character set forth, a moistener device comprising a hollow clip, means for supporting said clip, an inner-form member, and a wick confined between the inner-form member and said clip.

95 5. In means of the character set forth, a hollow clip, means for supporting said clip, a stirrup pivotally connected with the lower portion of said clip, an inner-form member, and a wick confined between said inner-form member and said clip.

100 6. In combination, a font, a bracket-member detachably mounted thereon, and an adjustable wick device carried by said bracket-member.

105 7. In combination, a font, a demountable bracket-member carried thereby, a hollow clip carried by said bracket-member, an expansible inner-form member received within said clip, and a wick adjustably confined between said clip and said inner-form member.

110 8. In a machine of the character set forth, moistening means comprising a water font having its front wall formed to provide a spout, a holder having slotted means engaging the upper portion of said water font, a moistener-element removably mounted in

said holder, and a co-acting presser-member loosely mounted on said holder.

9. In a machine of the character set forth, moistening means comprising a water font, 5 a holder mounted on the front portion thereof and equipped with a clip depending into the font, a wick adjustably mounted in said clip, and a presser-member having its rear portion loosely pivoted on said holder and 10 having its front end-portion co-acting with said wick.
